MOVABLE WORKTABLE FOR PRESSES

Harold E. Folkerth, Sr., Dayton, Ohio

Application April 8, 1949, Serial No. 86,183

4 Claims. (Cl. 164—117)

1

This invention relates to a feeding device and more particularly to a feeding device for feeding a work piece into successive operative positions.

The object of the device disclosed herein is to provide a mechanism for accurately positioning a work piece in a plurality of positions in stepped relation, the work piece being fed in successive steps both in-rows and tiers, the mechanism automatically presenting the work material in each of the positions without the attention of the operator, said mechanism operating in synchronism with the tool operating upon the work piece, such as a drill, punch, die, or any other suitable work tool. This has been accomplished by the use of a pair of cams, one of which actuates a work table in one direction through a plurality of steps, the other of which actuates the work table in a transverse direction upon the completion of the movement of the work table in the first direction, the cams operating alternately, one cam actuating the table in a plurality of steps in sequence in one direction, the other actuating the work table only one step in a transverse direction between each sequence of steps.

Other objects and advantages reside in the construction of parts, the combination thereof and the mode of operation, as will become more apparent from the following description.

Referring to the drawings,

Figure 1 is a top plan view of a work table and the control mechanism therefor for use with a drill press, a punch press or any other suitable tool, the tool having been omitted from the disclosure.

Figure 2 is a fragmentary cross sectional view taken substantially on the line 2—2 of Figure 1.

Figure 3 is a fragmentary cross sectional view taken substantially on the line 3—3 of Figure 1.

Figure 4 is a fragmentary cross sectional view taken substantially on the line 4—4 of Figure 1.

Figure 5 is a schematic wiring diagram used in controlling the movements of the work table.

In the drawings, the reference character 10 indicates a bed or a frame for supporting the mechanism used in association with the work feeding device. As may best be seen in Figures 2 and 3, a base 12 is supported upon the bed 10. This base 12 supports a guide member 14 provided with a dovetail groove 16 receiving a dovetail guide portion 18 of a movable member 20. This movable member 20 is provided with an upwardly directed transversely disposed dovetail guide portion 22 seated in a dovetail groove in the work table 24. Members 12 and 14 are stationary and always remain in fixed relation with respect to

2

the frame 10. Movable member 20 is mounted for longitudinal movement with respect to the guide member 14. The work table 24 is mounted for transverse movement upon the movable member 20.

As may best be seen by referring to Figure 2, the work table 24 is always biased to the right, as viewed in this figure, by a pair of compression springs 26, only one of which has been shown, 10 engaging the heads of plungers 28 mounted for reciprocatory movement in bearings 30 and abutting stop members 32 fixedly attached to the base 12. Movable member 20 is always biased to the left, as viewed in Figure 3, by a pair of plungers 34, spring urged in a manner identical to that disclosed in connection with the plungers 28. Each of the plungers 34 engages a stop 36, fixedly attached to the bed or frame 10. The driving mechanism for intermittently operating members 20 and 24 will now be described.

An electric motor 40, mounted on a frame 41, actuates a speed reducing gear mechanism 42, having an output shaft 44 keyed to a clutch member 46. A shaft 48 is journaled in suitable bearings in a standard 50 mounted on the frame 41 and in a standard 52 mounted on the bed 10. The shaft 48 has one end rotatably mounted in the clutch member 46, so as to maintain alignment. A complementary clutch member 54 is splined to the shaft 48 and may be actuated by a yoke 56 electromagnetically controlled by an armature 58 of a solenoid 60 into engagement with the clutch member 46, so as to drive the shaft 48 from the motor 40 whenever the clutch members are in engagement.

The shaft 48 has keyed thereto a cam member 62 actuating a cam follower 64 mounted for reciprocatory movement in a bearing 66 in the standard 50. The end of the cam follower 64 engages the side of the work table 24, so that as the cam member 62 is rotated from one cam surface level to another cam surface level, the table is either actuated away from the cam by the cam follower or actuated towards the cam by the compression spring 26, depending upon whether successive cam surface levels have an increasing radius or a decreasing radius. Each of the cam surface levels is arcuate. When the radius is increasing from one cam surface level to another, the work table 24 is actuated away from the cam, so as to progressively compress the spring 26 and retract the plungers 28. This takes place during half of a revolution of the shaft 48. During the other half of the revolution of the shaft, the cam follower recedes, so as

to permit the work table to move in step towards the cam. The cam surface 62a is an arcuate surface centered on the axis of rotation of the shaft 48. The cam surface 62b is another arcuate cam surface on another level, that is, the radius of the arcuate surface 62b is also centered on the axis of rotation of the shaft 48. The radius of the arcuate surface 62b is less than the radius of the arcuate surface 62a. Between the arcuate cam surfaces 62a and 62b is a cam follower actuating surface 63 used in moving the cam follower 64 from one cam surface level to another level. The cam surfaces 62b, 62c, 62d and 62e have radii progressively decreasing in length. The radii of the cam surfaces 62f, 62g and back to 62a progressively increase in length, for reasons which will appear more fully later.

A bevelled gear 70 is keyed to the end of the shaft 48 and meshes with a pinion 72 keyed to a shaft 74 journaled in suitable bearings in the standard 52 and having keyed thereto a pair of cams 76 and 78. The gear ratio of the gears 70 and 72 is such that the cam 76 will make one-half revolution during the period of time that the cam follower 64 passes over one cam surface. For example, the cam 76 will actuate the table 24 and movable member 20 through four steps while the cam follower 64 passes over one cam surface 62a or any one of the other cam surfaces 62b to 62f. A cam follower 80 is interposed between the cam 76 and the work table 24, so that as the cam 76 rotates, the cam follower 80 actuates the work table 24 in one direction. During the other half revolution of the cam 76, a spring (not shown) interposed behind the plunger 34, actuates the work table and member 20 towards the cam 76.

As may best be seen by referring to Figures 1, 3 and 5, a microswitch 82 is provided with a switching element or cam follower 84 contacting the cam 78. This cam 78 is provided with a plurality of notches 86, there being one notch for each of the cam surfaces 76a, 76b, 76c, 76d, 76e, 76f, 76g (not shown) and 76h. Whenever the cam follower 84 of the microswitch 82 drops into a recess, it actuates the microswitch 82. This microswitch 82 is a 2-way switch, as shown in Figure 5. For example, the switching element or cam follower 84 may be spring urged by means of a spring 85, as shown schematically in Figure 5, and terminates in a hook 88 engaging a lobe or ratchet tooth in member 90 mounted on the shaft 92 used in actuating the switch.

The 2-way switch 82 in one position is connected to a line 94 and when actuated into another position is connected in a line 96. These lines are connected to two poles of a 2-way switch 100 actuated by means of a shaft 102 provided with a ratchet 104 actuated by a pawl 106 that is preferably connected to the drill press head or the punch press head in such a manner that whenever the punch press operates, it switches the contacts from one line 94 to line 96 or vice versa.

The common terminal of the switch 100 is connected to the input circuit. The other line of the input circuit is connected to the electromagnet or solenoid 60 having the other terminal connected by a line 110 to a pair of microswitches 112 and 114, both normally closed. These microswitches 112 and 114 are mounted within a suitable cavity in member 12. The work table 24 has mounted therein a downwardly directed pin 116 that is free to travel within a slot 118 in member 20, this slot 118 extending parallel to the

dovetail guide 22. Furthermore, the pin 116 extends into an annular aperture 120 in members 12 and 14. The slot 118 has been shown in dotted lines in Figure 1 and the annular aperture 120 has been shown as a dotted circle in Figure 1.

Whenever the work table reaches one extremity, the pin 116 actuates the microswitch 112, so as to open-circuit the line through the solenoid 60. This is to arrest the operation of the machinery whenever all of the holes have been drilled or punched in a work piece. Another work piece is then placed in the machine and the circuit closed by means of a push button switch 130 connected in parallel across the two microswitches 112 and 114, which causes the work table to reverse its path to drill holes in the new work piece an identical pattern to the previous work piece, but in a reverse direction, until the pin 116 actuates the microswitch 114. The entire operation on the work piece represents one-half revolution of the cam 62. The second piece is controlled by the other half of the cam 62 causing the work table and the cams to move into the position in which they are found when the first work piece was put into the machine. In other words, when the cam 62 rotates through one revolution, it represents two half cycles, each half cycle completing the operation on a work piece.

The circuit arrangement shown in Figure 5 is schematic and merely shown for the purpose of illustration. Any other suitable circuit arrangement accomplishing the same results could be used.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

- An actuating device for actuating the work table to present work to an operating tool such as a drill press, punch press and the like, said actuating device including a cam, electromagnetically controlled clutch mechanism for intermittently rotating the cam, a cam follower actuated by the cam, said cam follower being connected to the work table so as to actuate the work table in response to changes in the contour of the cam, a second cam, means for driving said second cam, said means including a gear mechanism whereby the second cam makes a predetermined number of revolutions while the first cam makes one revolution, and a second cam follower actuated by the second cam, said second cam follower engaging the work table so as to move the work table in a direction normal to the movements imparted to the work table by the first cam follower, said second cam imparting a series of movements to the work table for each movement of the work table by the first cam.

- A work feeding mechanism for feeding a work piece intermittently to an operating tool, said work feeding mechanism including a work support mounted for transverse movements, a pair of cams, cam followers extending from the cams to the work support, each of said cams having a series of concentric cam surfaces, successive cam surfaces progressively increasing in diameter throughout one-half of the cam and

progressively decreasing throughout the other half of the cam, means for intermittently driving one of the cams, and a change speed device for connecting the other cam to said one cam, said change speed device causing said other cam to make a predetermined number of revolutions while the first cam makes one revolution, said cams rotating in planes at right angles to each other, one of said cams intermittently actuating the work table in one direction through a series of steps during one-half of a revolution, after which the other cam actuates the work table in a direction normal to said first direction through one step.

3. An actuating device for actuating the work table to present work to an operating tool such as a drill press, punch press and the like, said actuating device including a cam, means for intermittently rotating the cam, a cam follower actuated by the cam, said cam follower being connected to the work table so as to actuate the work table in response to changes in the contour of the cam, a second cam, means for driving said second cam, said means including a gear mechanism whereby the second cam makes a predetermined number of revolutions while the first cam makes one revolution, a second cam follower actuated by the second cam, said second cam follower engaging the work table so as to move the work table in a direction normal to the movements imparted to the work table by the first cam follower, said second cam imparting a series of movements to the work table for each movement of the work table by the first cam, and resilient means for urging the work table in a direction opposing the movement of the cams.

4. A work feeding mechanism for feeding a

work piece intermittently to an operating tool, said work feeding mechanism including a work support mounted for transverse movements, a pair of cams, cam followers extending from the cams to the work support, each of said cams having a series of concentric cam surfaces, successive cam surfaces progressively increasing in diameter throughout one-half of the cam and progressively decreasing throughout the other half of the cam, means for intermittently driving one of the cams, a change speed device for connecting the other cam to said one cam, said change speed device causing said other cam to make a predetermined number of revolutions while the first cam makes one revolution, said cams rotating in planes at right angles to each other, one of said cams intermittently actuating the work support in one direction through a series of steps during one-half of a revolution after which the other cam actuates the work support in a direction normal to said first direction through one step, and resilient means for urging the work support in a direction opposing the movement of the cams.
